DEWITT CLINTON HARLOW, OF HANNIBAL, MISSOURI.

Letters Patent No. 110,033, dated December 13, 1870.

IMPROVEMENT IN WASHING-MACHINES.

The Schedule referred to in these Letters Patent and making part of the same.

To all whom it may concern:

Be it known that I, DEWITT CLINTON HARLOW, of Hannibal, in the county of Marion and State of Missouri, have invented a new and useful Improvement in Washing-Machines; and I do hereby declare that the following is a full, clear, and exact description thereof, which will enable others skilled in the art to make and use the same, reference being had to the accompanying drawing forming part of this specification.

The object of this invention is to provide simple and cheap apparatus to be used in connection with the common wash-tub for washing clothes, and consists in revolving a spring cylinder above a concave, formed of rollers, as hereinafter described.

In the accompanying drawing—

Figure 1 represents a vertical longitudinal section of the machine, taken on the line *xx* of fig. 2.

Figure 2 is a vertical cross-section, taken on the line *yy* of fig. 1.

Similar letters of reference indicate corresponding parts.

A and B are head-blocks, which support the cylinder and concave of the machine.

C is the cylinder, which may be fluted or serrated, or covered with fluted or serrated sheet metal, as may be found most advisable.

D is a bed-piece, which connects the two heads A and B together.

E is the concave, which is composed of rollers F, (more or less in number.)

These rollers have journals or pivots at their ends, and revolve by the action of the cylinder over the clothes. The clothes to be washed are placed between the cylinder and the concave, the former being revolved back and forth by means of the crank G.

H is a gear-wheel on the end of the cylinder-shaft.

I is a shaft which extends across the machine above the cylinder, upon which there is a pinion-wheel J, which engages with the wheel H. The crank G is on the end of this shaft.

The journal of the cylinder and of the shaft I revolve in boxes, which are confined in vertical slots in the heads so that they may have a vertical motion.

K is a spring, which extends across the machine above the shaft G, the ends of which bear upon the journal-boxes.

This arrangement is seen in fig. 1, where L L represent the boxes.

M is an adjusting-screw, which works through the cap-piece N, by means of which more or less pressure may be brought to bear upon the cylinder and on the clothes beneath it.

O is the tub in which the above-described machine is placed for washing.

The machine is fastened in the tub by means of spurs in one of the heads and a button on the other, or in any other suitable manner.

By this arrangement clothes of any description may be cleansed, from the largest to the smallest piece, and any particular spot or portion may receive particular attention by this mode of washing.

Having thus described my invention,

I claim as new and desire to secure by Letters Patent—

The heads A B, cylinder C, bed D, concave E, shaft I, gear-wheels H and J, and spring K, arranged to operate substantially as and for the purposes herein shown and described.

D. C. HARLOW.
